DESIGN FOR A GLOVE

Marjorie Dunton, New York, N. Y.

Application February 10, 1939, Serial No. 82,913

Term of patent 3½ years

To all whom it may concern:

Be it known that I, Marjorie Dunton, a citizen of Great Britain, residing in New York city, in the Borough of Manhattan, county and State of New York, have invented a new, original, and ornamental Design for a Glove, of which the following is a specification, reference being had to the accompanying drawing, forming part thereof, wherein,

The characteristic feature of my design resides in the combination on the glove as shown of the ribbon thumb insert and matching bow portion, arranged in the manner disclosed.

I claim:

The ornamental design for a glove, substantially as shown and described.

MARJORIE DUNTON.
